UNITED STATES PATENT OFFICE.

WILLIAM R. TOWSE, OF LOUISVILLE, KENTUCKY.

SAW-HANDLE.

SPECIFICATION forming part of Letters Patent No. 364,452, dated June 7, 1887.

Application filed January 6, 1887. Serial No. 223,583. (No model.)

To all whom it may concern:

Be it known that I, WILLIAM R. TOWSE, a citizen of the United States, residing at Louisville, in the county of Jefferson and State of Kentucky, have invented a certain new and useful Improvement in Saw-Handles, of which the following is a specification.

My invention relates more particularly to an improvement in oil-cups for saw-handles and the method of connecting the same, and is especially designed as an improvement over my former invention, for which Letters Patent were granted me by the United States, No. 323,833, under date of August 4, 1885; and the objects of my invention are, first, to provide a simple and neat form of oil-cup, so constructed as to admit of its being firmly embedded and secured within the handle of a handsaw, and in so doing to obviate the necessity of cutting a large hole through the rear end of the saw-blade for the passage of the cup, which tends to weaken the same; second, to detachably secure within the cup a saw-oiler of such material as to readily absorb and hold the oil within the cup, and of such construction as to facilitate the handling of the same when the saw is being greased or oiled. These objects I accomplish in the manner illustrated in the accompanying drawings, in

30 which—

Figure 1 is a side elevation of a saw-handle having my improvement therein. Fig. 2 is a sectional view of a portion of a saw-handle and the cup. Fig. 3 is a sectional view of the cup, taken at right angles with Fig. 4, on line $x x$ thereof. Fig. 4 is a front view of the cup, showing the oiler therein. Fig. 5 is a sectional view of the oiler.

Similar letters refer to similar parts throughout the several views.

a represents a shallow metallic cup, having a circular flange, b , about its outer or open end, and having projecting from the under side of said flange, at suitable points thereon, 45 a number of short lugs, c , each of which is provided with a screw-hole, c' . Made to project from the bottom of the cup, and cast therewith at a point preferably slightly out of the center therewith, is a screw, d . Formed 50 on the inner surface of the flanged portion b of the cup is a continuous groove, e .

Formed in one of the flat sides of the saw-

handle g , and preferably near the center of its forward portion, is a depression extending to within a short distance of the saw-blade, and of the desired shape to admit of the insertion of the cup a therein until the outer surface of the lugs c are flush with the surface of the handle, the screw d being made to pass through a bolt-hole extending transversely through the saw-handle g and blade g' from the bottom of said depression, and being made to engage at its outer end with the threads formed on the inner surface of a nut, h , the latter having a flaring head countersunk in the side of the saw-handle, and having a short neck projecting into an enlargement of the bolt-hole.

The attachment of the cup to the handle is made additionally secure by screws i , made to pass through the holes c' in the lugs c into the handle, as shown in Fig. 2 of the drawings. These lugs c operate to strengthen the handle and prevent any tendency of said handle to split, which might be caused by the formation of the cup-hole therein. I preferably cause the screw d to project from the bottom of the cup at a short distance from the center thereof, so that in attaching my invention to old saw-handles one of the old bolt-holes, which are seldom formed exactly in the center of the handle, may be utilized, and at the same time give the cup a central location, as shown in Figs. 1 and 2 of the drawings.

k represents the oiler, which may be formed of felt, sponge, or other well-known soft and porous material, which is shaped to fit snugly within the cup a . The upper side of the oiler is cut away to form a depression on each side of a central upwardly-projecting ridge or tongue, m . This tongue m is tightly clamped between the halves of a bent thin metal plate, n , which, above the tongue m , is also made to inclose a short wire, o , which is preferably soldered therein, and which has its ends projecting slightly outward.

Formed on the inner edges of the flange b of the cup, at opposite points, are notches q , said notches opening into and being of a corresponding depth with the groove e . The length of the wire o being greater than the diameter of the inner circumference of the flange b , the oiler is inserted and detachably secured within the cup by allowing the projecting ends

of the wire *o* to enter the notches *q*, and then turning the clamp *n*, the upper portion of which serves as a handle, until the projecting ends of the wire have traveled the desired distance away from the notches *q* in the groove *e*, as shown in dotted lines in Fig. 4 of the drawings.

It will be seen that the oiler *k*, having first been thoroughly saturated with oil or grease, may be readily withdrawn from its position in the cup by turning the clamp *n* until its wire ends *o* may escape through the notches *q*, and utilized to grease the saw-blade, after which it may be returned to its position in the cup and secured therein in the manner before described.

Having now fully described my invention, what I claim, and desire to secure by Letters Patent, is—

The combination of the cup *a*, located within the saw-handle *g*, having lugs *c*, rearwardly-projecting screw *d*, the nut *h* engaging therewith, groove *e*, and notches *q*, with the oiler *k*, having tongue *m*, clamp *n*, and wire *o*, substantially as and for the purpose specified.

WILLIAM R. TOWSE.
